Inventor:
Henry Jung,
By John Chas Jones,

Attorney.

UNITED STATES PATENT OFFICE.

HENRY JUNG, OF NORWOOD, OHIO.

MACHINE-REAMER.

1,324,553.

Specification of Letters Patent.

Patented Dec. 9, 1919.

Application filed June 20, 1919. Serial No. 305,600.

To all whom it may concern:

Be it known that I, HENRY JUNG, an alien German, and a resident of Norwood, in the county of Hamilton and State of Ohio, have invented a certain new and useful Improvement in Machine-Ramers, of which the following is a specification.

This invention relates to machine-reamers, or more especially to those of the expansion, 10 radially-adjustable cutter-blade type and to include hand-reamers as well; and the object and consistency thereof are to provide a circumferential series of cutter-blades that are set free to be moved or slid both length- 15 wise and radially in open, longitudinal slots or narrow seat-ways made in the outer end of the reamer-head, such cutter-blades having inclined or sloped inner longitudinal edges, and to further provide a conical 20 spreader that is free to be reciprocated or slid along the outer tip-end of the reamer-spindle and whose face coincides in degree with that of the inner sloping longitudinal edges of the cutter-blades, a pilot-ring or 25 carrier-sleeve for use in adjusting the said spreader along the said outer tip-end of the spindle and having a deep peripheral flange or rim, a ring or washer detachably secured to the open-slotted end of the reamer-head 30 and having set-screws whose inner ends are adapted to engage the outer ends of the cutter-blades for holding the latter in adjusted longitudinal position in their respective slots or narrow seat-ways and the said 35 deep flange or rim on the pilot-sleeve contacting with the outer face of the said washer to cover the screw-heads and thereby prevent the accidental retreat or withdrawal of the screws themselves, and a lock-nut on 40 the extreme outer, screw-threaded tip-end of the spindle for preventing the conical spreader and its carrier-sleeve retreating from set position on the said spindle when the reamer is in an operative state, ready for 45 and during actual use.

The details of structure will be fully hereinafter described and then more particularly pointed out in the claims that follow.

In the accompanying sheet of drawings,— 50 Figure 1 is a longitudinal elevation of my improved reamer, the same being shown, however, in horizontal position and with its cutter-blades in their innermost or slightest expanded position in the head;

55 Fig. 2, an axial longitudinal section of

the reamer-head and with the spindle in elevation;

Fig. 3, a transverse section taken on the dotted-line 3, 3, of Fig. 1;

Fig. 4, a transverse section taken on the 60 dotted-line 4, 4, of Fig. 1;

Fig. 5, a fore-end elevation of the device;

Fig. 6, a side elevation of the conical cutter-blade spreader or expander forming one of the main features of the invention 65 herein; and—

Fig. 7, a perspective view of one of the cutter-blades shown in its preferred form.

In these views, 8 indicates the usual mounting-end of the spindle, having the reduced fore-portion 9 and the still further reduced fore-end or extreme tip 10, the latter being screw-threaded part length, as best seen in Fig. 2.

11 indicates a tubular head or sleeve keyed 75 to the portion 9 of the spindle and extending forwardly over the reduced tip-end 10 of said spindle so as to leave an annulus 11^a for accommodating a conical spreader 12 whose circular rear-extension 13 is outwardly screw-threaded and it has a smooth bore for enabling it to pass freely along the said tip-end 10 of the spindle, as best seen in Fig. 2.

That part of the tubular head or sleeve 85 11 extending over the tip-end 10 of the spindle is provided with a circumferential series of equidistant longitudinal slots or narrow seatways 14 to accommodate cutter-blades 15 whose outer edges extend normally 90 a slight distance beyond the outer face or periphery of the said tubular head or sleeve 11 and whose inner edges are sloped, as shown at 16, to correspond to the slope of the conical spreader 12, the slope of both 95 being preferably, but not essentially, ten degrees, which is sufficient to facilitate the outward expansive movement of the cutter-blades beyond the face or periphery of the head 11.

100 A ring or washer 17 is fastened by means of screws 18 to the outer end of the open-slotted head 11 and additional set-screws 19 are used in said ring for independently holding the cutter-blades 15 in their seat-ways 14 against longitudinal movement, as well as outward radial movement, the cutter-blades being by preference a little shorter than the length of the seat-ways when it is 105 the intention that the said ring shall not bear 110

directly in contact with the cutter-blades in the use of the tool and it being further intended to use the width or thickness of the ring, as well as the slight space 15^a between the outer ends of the cutter-blades and the ring to afford an advance aligning-bearing for the tool in the hole to be reamed out and forming an important feature of my invention herein. The set-screws 19 have no heads, but the fastening-screws 18 have inwardly-beveled heads that engage countersunk openings made in the outer face of the ring or washer 17 so that they may seat flush with the said outer face of the washer. Ordinarily, three of the fastening-screws 18 are sufficient, and, of course, a set-screw 19 for each cutter-blade, as best shown (dotted) in Fig. 5. As thus far specifically described, the cutter-blades are best approached for inserting and adjusting in their seat-ways by simply loosening the set-screws 19 and manipulating the conical spreader 12 backward or forward to suit the distance the said cutter-blades shall project beyond the face of the head 11, the said slight space 15^a provided by making the blades shorter than their seat-ways being utilized for the insertion of a pointed instrument and the ready movement of the blades to suit the position they are to occupy in the head effected.

Thus the ring or washer 17 need not be removed from place on the end of the head, unless it be otherwise desired to remove the blades lengthwise from their seat-ways and replaced by others or for repairs.

To enable a ready adjustment of the blades, especially outwardly in their seat-ways, I provide a pilot-ring 20 that is internally screw-threaded for engagement with the outwardly-threaded extension 13 of the conical spreader 12, a multiple flat-faced formation, hexagon nut-fashion, 21 being constructed on the outer portion of the pilot-ring for the use of a wrench in applying the pilot-ring to and fro along the said threaded rear-end 13 of the spreader. The pilot-ring is further provided with a flange 22 of sufficient diameter to cover the face of the ring or washer 17 and thus effectually prevent the escape of the screws from the said washer 17 when the parts of the device are assembled and in use.

An outer lock-nut 23 is mounted on the threaded end of the spindle tip 10 to close and hold the pilot-ring 20 in place on the threaded extension 13 of the conical spreader 12, and, in turn, said conical spreader in expanded position in contact with the sloped inner faces of the blades, and, also, to hold the flanged inner face of the said pilot-ring 20 in contact with the outer face of the washer 17 for the purpose above described in connection with preventing the release of the screws from place in said washer.

An elongated pin 24 extends from the face of the conical spreader 12 for engagement in the annulus 11^a of the head or sleeve 11 between the inner sloped edges of any adjacent pairs of blades 15, as best shown in Fig. 4, but well shown, otherwise, in Figs. 2, 3 and 6, for the purpose of preventing the rotation of the conical spreader when it is desired to rotate the pilot-ring 20 for advancing or retreating it along the threaded rear-extension 13 of said spreader, and especially when it is desired to use the spreader in expanding or outwardly-protruding the cutter-blades for reaming out bores of larger diameters.

It is obvious, without going into any lengthy detailed description, that the structure herein is well adapted for use as a hand-reamer, or as an expansible-tap for varied uses, the cutter-blades being adapted to be made quite long for the hand-reamer, or longer than for the machine or power-driven reamer.

I claim:—

1. A reamer comprising a spindle, a head or sleeve keyed thereto, a partially threaded shoulder tip at the outer end of said spindle, open slots or seat-ways in said head or sleeve, cutter-blades having sloped inner edges and freely engaging the said open slots or seat-ways, a ring or washer mounted on the outer open-slotted end of the said head, fastening-screws in said washer, set-screws in said washer for holding the cutter-blades in adjusted position to suit the diameter of hole to be reamed, an annulus between the said tip of the spindle and the open-slotted end of the said head, a conical spreader provided in said annulus and having a smooth bore for free reciprocal-engagement over said spindle-tip and in contact with the inner sloped edges of the said cutter-blades, a threaded rear-extension on said conical spreader, a pilot-ring having threaded-engagement with the said threaded rear-extension on the conical blade-spreader, and means on the outer end of the spindle-tip for engagement with the said pilot-ring for holding it in adjusted position in connection with the expanded or protruded cutter-blades to suit the desired bore of the hole to be reamed.

2. A reamer comprising a shouldered spindle having a reduced outer end or tip that is partially screw-threaded, a cylindrical head or sleeve keyed to the spindle to the rear of said tip, open slots or seat-ways in the outer end of said head beginning in line with the inner end of said spindle-tip and extending part way only the length of said tip, an annulus between the said spindle-tip and the open-slotted end of said head, cutter-blades mounted free to be moved in said open slots or seat-ways and having sloped inner edges, a ring or washer

deachably-mounted on the outer open-slotted end of the head, set-screws in said ring or washer for holding the cutter-blades in adjusted position in the open-slotted end of the head, a conical spreader in said annulus and having a smooth bore for free reciprocal-engagement over said spindle-tip and in expanding or outwardly-spreading contact with the inner sloped edges of the cutter-blades, a threaded rear-extension on said conical spreader, a pilot-ring having threaded-engagement with the said threaded rear-extension on the conical blade-spreader, a flange along the periphery of said pilot-ring 15 to contact with the outer face of the said washer and to prevent the outward escape or retreat of the screws in said washer, a lock-nut on the outer end of the spindle-tip for engagement with the outer face of said pilot-ring and to hold the cutter-blades in 20 adjusted position, and a stop-pin on the conical spreader for lateral engagement with the sides of the inner edges of any adjacent pairs of cutter-blades to prevent the turning of the conical spreader on the spindle- 25 tip when the pilot-ring is turned along the threaded rear-extension of the said conical spreader in the adjustment of the said cutter-blades.

HENRY JUNG.
